UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

OVERHEAD TRACK-JOINT AND SUPPORTING MEANS THEREFOR.

1,156,472.

Specification of Letters Patent.

Patented Oct. 12, 1915.

Application filed February 19, 1915. Serial No. 9,284.

To all whom it may concern:

Be it known that I, HENRY L. FERRIS, a citizen of the United States, residing at Harvard, in the county of McHenry and State of Illinois, have invented a new and useful Improvement in Overhead Track-Joints and Supporting Means Therefor, of which the following is a specification.

My invention relates to improvements in over-head track, and more particularly to a means for joining different kinds of track.

More immediately the invention is concerned with that type of overhead track which is used for litter carriers, feed carriers and the like in barns, and to the means used for joining such track to the out-door track extensions.

The invention further relates to a preferred means for supporting and guying the joint between such indoor and outdoor tracks.

The indoor track commonly made use of for such service as I have mentioned will generally be rigid track, either of elongated C-section, tubular, I-section, or some rolled or drawn shape, and provided at intervals with rigid supports which will commonly be attached to the roof-beams of the structure. The outdoor track commonly used in connection with such indoor track for the purpose of permitting the litter carriers, or the like, to be transported to a suitable dump outside of the building is usually of so-called "flexible" construction, and may either be of rolled or drawn rod or wire, or of steel cable, supported only at the ends. The indoor and outdoor track commonly meet at the door apertures of the building, and it is the specific object of my invention to provide a structure adapted for mounting at the door aperture and forming an alining joint between the rigid and the flexible track and a supporting and guying means for the end of the flexible track.

More particularly it is the object of my invention to provide such a joint, which will be simple and durable in construction and capable of maintaining the two tracks in perfect alinement.

Other objects and advantages of my invention will appear more fully from the following detailed description of several different embodiments of the invention.

These various embodiments of the inven-

tion are illustrated in the accompanying drawings, in which:

Figure 1 is a side elevation of a combined track support and joint, constructed in accordance with the invention, the door beam to which the structure is attached and the adjacent wall of the building being shown in section; Fig. 2 is a section on the line 2 of Fig. 1; Fig. 3 is a section on the line 3 of Fig. 2; Fig. 4 is a side elevation of a form of track joint constructed in accordance with my invention and adapted for use with an I-section track; Fig. 5 is an enlarged longitudinal section through the track joint and support shown in Fig. 4; Fig. 6 is an elevation of another form of track joint embodying my invention and adapted for use with tubular track; Fig. 7 is an enlarged longitudinal section of the structure shown in Fig. 6; Fig. 8 is a schematic sectional view of a barn structure showing another form of track joint and one manner in which the rigid track may be guyed when this joint is used; Fig. 9 is an enlarged longitudinal section of the track joint shown in Fig. 8; Fig. 10 is an enlarged elevation of the end rail hanger and joint of the construction shown in Fig. 8; Fig. 11 is a section on the line 11 of Fig. 10; Fig. 12 is a section on the line 12 of Fig. 10, and Fig. 13 is a section on the line 13 of Fig. 10.

Referring first to the construction shown in Figs. 1 to 7 of the drawings: 10 designates a horizontal beam such as is employed as the top member of a door-frame, and 11 designates the wall of the building. Bolted to the beam 10, as by the bolts 12, is an angular bracket or hanger 13, rectangular in cross-section, as shown in Fig. 2, and inclining inwardly from the door beam 10 to which it is secured. At its lower end the bracket or hanger 13 had formed thereon a hood 14 which serves to secure the supporting guy 15, which may be fastened to a beam or other support. The combined track support and joint shown in Figs. 1 to 7 comprises a casting designated as a whole by the numeral 16, and consisting of a T-shaped section 17 having one rounded end 18, one tapering end 18', and a web 19 which carries a securing flange 20 adapted to be bolted, as by the bolts 21, to the face of the bracket or hanger 13, the bolt-holes 22 for the bolts 21 in the flange 20 being formed

as arcuate slots to permit of slight variations in the angular position of the track-support with relation to the hanger. The T-head 17 of the track-support 16 has bent therearound 5 a flexible track member 23, which is illustrated in the drawing as being formed of light rod, the bend being such that the track shall tightly embrace three sides of the T-head, as best shown in Fig. 3, and the outwardly extending portion of the track shall lie along the top edge of the T-head. In order to secure the bent portion of the flexible track 23 in position about the T-head 17, I employ the C-section element shown in 10 Fig. 2 and designated 24. As illustrated by the drawing, this elongated C-section completely surrounds the T-head and the length of flexible track bent therearound, and embraces the web 19 which joins the T-head to 15 the supporting flange 20. The tapering end 18' of the T-head which points outwardly beneath the extending portion of the track 23 serves to more effectively guard against bending of the track under load. This extension 18' may well be omitted, however, in 20 most cases. To secure the C-section 24 in position I may employ a bolt 25, which passes through a bore within a central enlarged portion 26 of the web 19 (see Fig. 3) 25 and has its head bearing upon the C-section and its nut bearing upon the hanger 13, so that in addition to securing the C-section piece in place this bolt acts as an additional support for the member 16 through its connection to the hanger 13. In the construction shown in Figs. 1, 2 and 3 this C-section element 24, which embraces the T-head 17 and secures the flexible track 23 thereto, is in 30 fact nothing more than the outer end of the rigid track 27 which extends within the barn. When the parts are assembled, as shown in Fig. 1, the rigid track is, therefore, continuous up to a point 28 which is just beyond the outer end of the track support 16, 35 and at this point the flexible track 23 issues from the interior of the rigid track 27 and passes outwardly in alignment therewith and substantially flush with the upper surface thereof. The track support 16 therefore 40 serves as a means for securing the meeting ends of the flexible and rigid tracks in alignment with one another and to provide a continuous upper surface upon which the trolley may run, and when in assembled position 45 the parts are locked in position by their engagement with one another in the simplest manner possible.

In the construction shown in Figs. 4 and 5 the rigid track 27' is a rolled I-section, the 50 web of which is perforated as shown at 29. In applying my device to this form of rigid track, the C-section piece 24 will be provided with two extensions 30 of appropriate cross-section to lie within the channels of the I-section track and bear against the op-

posite faces of the web thereof, the two extensions 30 being held against the I-section by a through-bolt 31 passing through alining apertures in these extensions and through one of the apertures 29 in the web 70 of the track-member. In the form of the invention shown in Figs. 4 and 5, the rigid track terminates at a point 32 and the upper edge of the C-section piece 24 carries the trolley to the point 28, at which the flexible 75 track emerges from the joint.

In the construction shown in Figs. 6 and 7, a rigid track 27" of tubular section is employed. For combination with such a rigid track I provide the C-section piece 24 80 of the joint with a nipple, or cylindrical boss, 34, projecting outwardly from one end and adapted to lie within the bore of the tubular track 27" and to be secured thereto, as by a pin 35. In this form of the invention also, the rigid and flexible tracks are secured and supported in alinement with each other by the T-head 17. In this construction the rigid track terminates at a point 36 at the inner end of the C-section 90 95 24 and the latter piece serves as a track member to carry the trolley to the point 28, at which the flexible track emerges from the joint.

In all three of the constructions illustrated in the drawings and described above the rigid and the flexible tracks are joined and held in alinement with one another by a single unitary device carried by the rigid track and adapted to be supported by any 100 common form of bracket or hanger, and in the preferred construction of this latter element a guy hook is provided by which the track may be guyed to resist the outward pull transmitted by the flexible track when 105 the load is carried by the same. In the form of track support shown in Figs. 4 to 7 the tapered extension 18' has been omitted.

In Figs. 8 to 13 I have illustrated one method of employing my improved track-joint without the use of any hanger or support directly connected therewith. In this embodiment of my invention a rigid track 27 of the preferred C-section is shown as supported at intervals by hangers 37 adapted to be bolted or otherwise secured to the beams 38 of the barn structure, and for connecting the hangers 37 to the track I may provide detachable foot-pieces 39 bolted to the slotted ends of the hangers as at 40. 110 115 For supporting the C-section track shown these foot-pieces will preferably have T-heads 41. It will be understood that if tubular or I-section, or track of other form, be used, the foot-pieces or track-supporting 120 125 ends of the hangers will be appropriately formed to secure such track.

For connecting the rigid track 27 with the flexible track 23 in this embodiment of the invention, the construction employed may 130

be substantially the same as that made use of in Figs. 1 to 7, excepting only that since the hanger 13 is not used, the spacing web 19 and securing flange 20 of the track-joint member may be omitted. Specifically, I prefer to make use of a filler-block 17' which lies within the end of the C-section track 27 and is secured thereto as by a pair of bolts 25'. This filler-block may have an 10 internal rounded end 18 and an externally projecting wedge-shaped end 18', similar in all respects to the T-head piece 17 which forms the filler-block in the other embodiments of my invention. In addition I may 15 form in the lower edge of the block 17' a notch or recess 42 which may receive an in-turned end 43 of the flexible track-member 23, for the purpose of better securing the latter. The rail-lengths which make up the 20 rigid track 27 may be joined by plates 44 which lie within the ends of the rails and are connected therewith by bolts 45, and for the purpose of securing this track against the longitudinal strains imparted to 25 it by the flexible track-member 23 when the latter is under load, I may provide a guy or tie-rod 46 fastened to the inner end of the rigid track and to the barn structure. In this embodiment of my invention as shown 30 in Figs. 8 to 13 therefor the flexible track and the rigid track are joined in such a manner as to lie in alinement and with their upper surfaces substantially flush with one another, while the track joint is supported 35 from the rigid track, and the pull of the flexible track is transmitted through the latter joint to the rigid track and by the latter transferred to the building structure. Without substantially altering the construction 40 of my track-joint therefore I am able to dispense with the joint-supporting bracket or hanger 13 shown in Figs. 1 to 7 and to support and guy the flexible track through the rigid track itself. In connection with this 45 form of my invention also it will be understood that any preferred form of rigid track may be used. Thus if the rigid track be of the tubular form or of the I-section form, as shown in Figs. 6—7 and 4—5, respectively, a joint member of appropriate form 50 as shown in these figures will be secured to the end of the track and the flexible track then secured within the joint member.

While I have shown and described in considerable detail three specific embodiments of my invention, it is to be understood that I do not regard my invention as limited to the details of construction shown and described, nor to any of them, except in so far 60 as I have included such limitations within the terms of the following claims, in which it is my intention to claim all the novelty inherent in my invention as broadly as the prior art will permit.

What I claim as new and desire to secure 65 by Letters Patent, is:

1. In apparatus of the class described, a rigid track, a flexible track, and a joint member securing the end of said flexible track to the end of said rigid track in the 70 vertical plane of and with its upper surface substantially flush with the upper surface of said rigid track.

2. In apparatus of the class described, a rigid track, a joint member carried by the 75 end of said rigid track and in the vertical plane of and substantially flush with the upper surface thereof, and a flexible track having its end secured to said joint member and extending outwardly therefrom in alinement with and substantially flush with the upper surface thereof, whereby the rigid track, joint member and flexible track lie 80 in a single straight line.

3. In apparatus of the class described, a rigid track, a hollow-joint member carried by the end of said rigid track, and a flexible track-member having one end secured in the vertical plane of and within the said hollow-joint member and extending outwardly therefrom in alinement with the said 90 rigid track.

4. In apparatus of the class described, a rigid track, a hollow-joint member carried by the end of said rigid track, a flexible 95 track having its end extending within the said hollow-joint member and return-bent in a vertical plane therein, and means for securing the bent end of the flexible track member within the said hollow-joint member. 100

5. In apparatus of the class described, a rigid track, a hollow-joint member carried by the end of said rigid track, a filler-block 105 lying within the said hollow-joint member, and a flexible track having one end entering the joint member and bent to embrace the filler-block therein, the said flexible track extending outwardly from the joint member in alinement with the said rigid track. 110

6. In apparatus of the class described, a rigid track, a flexible track, a joint for securing the end of said flexible track to the end of said rigid track and in a vertical plane therewith, and means for guying the 115 rigid track against the tension of the said flexible track.

7. In apparatus of the class described, a hanger, a track joint carried by said hanger, a flexible track secured to the said track joint in the vertical plane thereof and extending outwardly therefrom, and a rigid track secured to the said track joint and extending outwardly therefrom in a direction opposite the said flexible track and having 120 its upper surface in alinement with and substantially flush with the said flexible track. 125

8. In apparatus of the class described, a

- hanger, a track joint carried by said hanger, a flexible track extending outwardly from the upper surface of the said track joint and having its extremity bent downwardly 5 in a vertical plane to embrace the same, and a rigid track member carried by said track joint and extending outwardly therefrom in a direction opposite said flexible track and having its upper surface in alinement and 10 substantially flush with the upper surface of the flexible track.
9. In an apparatus of the class described, a hanger, means for securing a guy to the free end of said hanger, a track joint carried by the said hanger, a flexible track extending outwardly from the upper surface of said track joint and having its extremity bent to embrace the same, and a rigid track member carried by said track support and 15 having its upper surface in alinement with and substantially flush with the upper surface of the said flexible track and extending outwardly from the track joint in a direction opposite thereto.
10. In apparatus of the class described, a hanger member, a T-section track-joint carried by said hanger member, a flexible track member lying along and extending outwardly from the top surface of the T-head of said joint and bent to embrace one end and the lower side thereof, a C-section clamping member lying over the bent extremity of said flexible track member and embracing the said T-head, and a rigid track 20 member supported by the said track-joint and in alinement with and flush with the upper surface of the flexible track and C-section.
11. In apparatus of the class described, a hanger member, a T-section track-joint carried by said hanger member, a flexible track lying along the upper surface of the T-head of said track-joint and extending outwardly therefrom, the said flexible track having its 25 extremity bent to embrace one end of the lower side of said T-head, a C-section clamping member lying over the bent extremity of said flexible track and embracing the said T-head, and a rigid track member carried 30 by said C-section clamping member and extending outwardly therefrom in a direction opposite to the said flexible track and having its upper surface in alinement with and

substantially flush with the upper surface of the said flexible track.

12. In apparatus of the class described, a hanger member, a T-section track-joint, means for securing the said track-joint to the said hanger, said means permitting of the angular adjustment of the parts, a flexible track lying along the upper surface of the T-head of said track-joint and extending outwardly therefrom, the extremity of said flexible track being bent to embrace one end and the lower surface of said T-head, a C-section clamping member lying over the bent extremity of the flexible track and embracing the T-head of the track-joint, and a rigid track member carried by the said track-joint and extending outwardly therefrom in a direction opposite the said flexible track and having its upper surface in alinement with and substantially flush with said flexible track.

13. In apparatus of the class described, a hanger, a T-head track-joint carried by the said hanger, a flexible track lying along the upper surface of the T-head of said joint and extending outwardly therefrom, the extremity of said flexible track being bent to embrace one end and the lower surface and said T-head, and a rigid track of C-section embracing the T-head and the bent extremity of the flexible track which lies thereover, whereby the rigid and flexible tracks are supported in alinement and with their upper surfaces substantially flush.

14. In apparatus of the class described, a hanger, a T-section track-joint carried by a side face of said hanger, a flexible track lying along the upper surface of the T-head of said track joint and extending outwardly therefrom, a clamping member embracing the said T-head and lying over the flexible track, a securing bolt for said clamping member, the said securing bolt passing through the T-head and through the web of the track support and into the said hanger, and a rigid track member carried by said track-joint and having its upper surface in alinement and substantially flush with the upper surface of said flexible track.

HENRY L. FERRIS.
